[57] CLAIM

The ornamental design for a coating thickness gage, as shown and described.

DESCRIPTION

FIG. 1 is a front elevational perspective view of the coating thickness gage;

FIG. 2 is a front plan view of the coating thickness gage of FIG. 1;

FIG. 3 is a left plan view of the coating thickness gage of FIG. 1;

FIG. 4 is a right plan view of the coating thickness gage of FIG. 1;

FIG. 5 is a top plan view of the coating thickness gage of FIG. 1;

FIG. 6 is a bottom plan view of the coating thickness gage of FIG. 1; and,

FIG. 7 is a back plan view of the coating thickness gage of FIG. 1.

The broken line showing of a flat surface fragment and a hand are for illustrative purposes only and forms no part of the claimed design.

FIG. 1

FIG. 2

FIG. 3

FIG. 4

FIG. 5

FIG. 6

FIG. 7
